(57) **CLAIM**

The ornamental design for a folding knife blade with
engagement ring, as shown and described.

DESCRIPTION

FIG. 1 is a perspective view of the ornamental knife blade
engagement ring according to the present invention.

FIG. 2 is a top plan view thereof.

FIG. 3 is a bottom plan view thereof.

FIG. 4 is a rear elevational view thereof; and,

FIG. 5 is a front elevational view thereof.

The broken line showing of the handle is provided for
purposes of environment and forms no part of the claimed
design.

1 Claim, 3 Drawing Sheets

FIG. 2

FIG. 3
